CLAIM

The ornamental design for secure video doorbell container
with anti-theft door hook, as shown.

DESCRIPTION

FIG. 1 is a perspective view of secure video doorbell
container with anti-theft door hook showing my new design;
FIG. 2 is a front view thereof;
FIG. 3 is a rear view thereof;
FIG. 4 is side view thereof;
FIG. 5 is another side view thereof;
FIG. 6 is a top view thereof;
FIG. 7 is a bottom view thereof;
FIG. 8 is another front view thereof, showing the secure
video doorbell container with anti-theft door hook with a
video doorbell contained therein and installed on a door;
and,
FIG. 9 is another rear view thereof, showing the secure video
doorbell container with anti-theft door hook installed on a
door.
The broken lines depict unclaimed environmental subject
matter.

1 Claim, 8 Drawing Sheets
